DESIGN FOR A TABLE

Carl E. Rosenfeld, San Francisco, Calif.

Application February 5, 1945, Serial No. 117,774

Term of patent 14 years

(Cl. D33—14)

To all whom it may concern:

Be it known that I, Carl E. Rosenfeld, a citizen of the United States of America, residing in the city and county of San Francisco, State of California, have invented a new, original, and ornamental Design for a Table, of which the following is a specification, reference being had to the accompanying drawing, forming part thereof.

The single figure in the drawing is a perspective view of the table, showing my new design.

I claim:

The ornamental design for a table, as shown.

CARL E. ROSENFELD.
